ELECTRICALLY LIGHTED GASOLINE
STATION TOY

Louis Marx, New York, N. Y.

Application January 23, 1934, Serial No. 707,901

8 Claims. (Cl. 46—39)

This invention relates to toys, and more particularly to an electrically lighted gasoline station toy.

The general object of my invention resides in the provision of a toy gasoline station which will be realistic in appearance and operation. More particular objects reside in the provision of simulated gasoline pumps, a toy lift or elevatable greasing rack, a portable pump, as for lubricating oil, and other accessories such as an air pump, which are customarily found at these stations. Still further objects center about the provision of electric lighting equipment for the toy, and are to illuminate the gasoline pumps in a manner resembling the lighted sign or advertisement ordinarily found on such pumps; to illuminate the lift or greasing stand; and to provide appropriate switch mechanisms for automatically illuminating the lift whenever it is elevated, and for optionally illuminating the pumps when desired.

To the accomplishment of the foregoing and such other objects as will hereinafter appear, my invention consists in the toy gasoline station elements as well as their combination and relation one to another, as hereinafter are more particularly described in the specification and sought to be defined in the claims. The specification is accompanied by drawings, in which:

Fig. 1 is a perspective view showing one form of toy gasoline station embodying features of my invention;

Fig. 2 is a plan view thereof; and

Fig. 3 is an enlarged section taken in the plane of the line 3—3 in Fig. 2.

Referring to the drawings the toy gasoline station comprises a base 12 having mounted thereon a building 14, a battery casing 16, a plurality of gasoline pumps 18, a lift or elevatable greasing stand 20, and other accessories including in the present case the compressed air stand 22, the portable 24, and water cans 26.

Considering the toy in greater detail, the base 12 is preferably made of sheet metal and flanged to form a curb 30 which is preferably pressed downwardly or cut away at 32 leading to the lift 20 in order not to unduly obstruct the driving of a toy automobile up onto the lift.

The house or building 14 is made of sheet metal walls secured to the base by appropriate tongue and slot connections, and a roof member similarly secured to the side walls by tongue and slot connections. In the present case the building may be opened by doors 34 and 36 forming the front wall of the building. The doors may be locked in closed position by an appropriate latch

38 controlled by a handle 40. This construction permits the child to place appropriate furniture and fittings in the building.

The battery casing 16 comprises a transversely curved sheet metal member 42 closed at one end by an insulation member 44 carrying a terminal 46 which bears against one end of a battery cell 48, and closed at its opposite end by a switch carrying lug or arm 50. The casing is preferably dimensioned to receive and hold in end to end contacting relation two battery cells 48 and 52 of the flashlight type. The support 50 carries pivotally mounted thereon a switch arm 54 having an in-turned end 56 adapted to bear against the zinc base of the cell 52 when the switch is closed. Switch arm 54 is preferably grounded, and, inasmuch as the circuits are preferably made single wire circuits, this grounding action energizes the illumination system of the toy.

The battery housing 16 is preferably located just behind the building 14 in order to partially conceal the same. The housing might, of course, be located in the building, thus concealing the same entirely, but I prefer to locate the same outside the building in order to provide play room in the building, as previously described, and for the further reason that the battery housing may itself be considered as simulating a tank at the gasoline station, as, for example, a compressed air tank supplying compressed air to the stand 22.

Each pump 18 comprises an upright hollow sheet metal body member 60 secured to the base by appropriate tongue and slot connections and closed at its upper end by a top or cover 62. The pump is further provided with a flexible rubber tube or strand 64 simulating a gasoline hose and having at its free end a nozzle simulating member 66. The side wall of the pump is preferably provided with means to receive and hold the nozzle 66, and in the present case this takes the form of a keyhole type slot 68 into which the end of the nozzle 66 may be passed and then moved downwardly to anchor the same in place.

The top 62 of the pump body is provided with an electric light bulb socket 70 one terminal of which is preferably grounded to the pump body, and the other terminal of which is connected by an insulated wire which extends downwardly through the pump body and beneath the base to the terminal 46 of the battery casing. These wires are clearly shown at 72 and 74 in Fig. 2. The sockets 70 have screwed thereinto the bulbs 76. These bulbs are preferably given a circular outline with flat sides in simulation of the advertising signs ordinarily provided at the top of

these gasoline pumps. Instead of providing a bulb within a flat circular casing, the evacuated bulb or envelope is itself given the desired configuration, said slot being so dimensioned as to 5 freely receive the nozzle at the enlarged part of the slot, but to hold the nozzle at the narrow part of the slot.

The lift 20 comprises a sheet metal member flanged to form a pair of spaced guide rails 80 10 interconnected by cross braces 82 which are preferably curved downwardly in the manner shown in Fig. 1. The rails 80 are straight when viewed in plan but are centrally elevated when viewed in profile, to provide inclined approach surfaces 15 84 clearly shown in Fig. 1, and symmetrically inclined ends 86 so that a toy automobile when run onto the lift will remain in place. The ends 86 are closed by flanges 88, but these flanges are, of course, omitted from the approach ends 84.

20 The elevatable part of the lift is mounted on base 12 by a parallelogram movement formed by arms pivoted at their lower ends on the base and pivoted at their upper ends on the lift. Specifically, one end of the lift is mounted on a 25 bent stiff wire 90 having outwardly bent lower ends journaled in lugs 92 struck upwardly from base 12, while the upper part of wire 90 is journaled in lugs 94 struck downwardly from rails 80. The other end of the lift is similarly carried 30 by a bent wire 96 journaled in bottom lugs 98 and in top lugs 100. Wire 96 is projected at one end to form an operating lever 102 which may be manually operated to elevate the lift. The opposite end of wire 96 is also preferably extended and appropriately bent to form a member 104 which acts as a stop limiting the turning 35 movement of the lift supporting arms when these arms are raised from a substantially horizontal position to a position a little beyond vertical dead-center. With this construction the lift remains stable in elevated position until lowered by manipulation of the control lever 102.

The lift is preferably illuminated by an electric light bulb 106. This bulb is received in a ground-45 ed support or socket 108. The insulated terminal of the socket is connected by wires 110 and 112 extending beneath base 12 to the common terminal 46 of the battery housing. It is desirable to illuminate the lift only when using 50 the same, and the circuit to lamp 106 is preferably interrupted by a series switch 114. In accordance with a further feature of the present invention, the switch 114 is automatically closed whenever the lift is elevated. With this object in view the switch blade 116 is preferably made resilient and compressible from a normal open-circuited position to close the lamp circuit. The blade 116 is positioned in the path of the stop member 104. This is provided at its end 55 with appropriate insulation 118. The switch 114, as is best shown in Figs. 2 and 3, consists of an insulation member secured to the sheet metal base 12 by appropriate tongue and slot connections; the blade 116 anchored at one end and 60 connected to wire 112 by a rivet or eyelet 120; and another eyelet 122 to which the wire 110 is connected and which acts as a contact cooperating with the blade 116. It will be manifest that when the lift is elevated, the stop 104 bears downwardly against switch 116, closing the same and lighting the lamp 106.

The gasoline station also includes the compressed air stand 22, which needs no detailed description, and also the portable oil pump 24. 70 This consists of a rectangular-sided body mount-

ed on a base plate 130 having wheels 132. The spindle of the front wheel 132 may be prolonged to form the pull handle 134. The tank or body is surmounted by a pump member 136 having an operating crank arm 138 thereon. The base 5 12 of the toy is preferably provided with slots 140, best shown in Fig. 2, for partially receiving the wheels 132 of the portable, thereby anchoring the same in its normal position. It will be understood that the portable may be intentionally moved out of the slots 140 and handled like a regular portable.

It is believed that the mode of constructing and using, as well as the many advantages of my gasoline station toy, will be apparent from the foregoing detailed description thereof. The toy with is openable house, its realistic gasoline pumps, its portable oil pump, and its elevatable greasing stand, possesses extensive play value apart from the electrical equipment. This play 20 value as well as the realism of the toy are greatly enhanced by the addition of the electric lighting equipment.

It will be understood that various combinations of the component parts of a gasoline station may 25 be employed, and these components may be differently arranged and located on the base of the toy. It will accordingly be apparent that while I have shown and described my invention in a preferred form, many changes and modifications 30 may be made in the complete structure disclosed as well as in the component parts thereof, without departing from the spirit of the invention, defined in the following claims.

I claim:

1. In a toy gasoline station, a pump comprising an upright hollow body member made of sheet metal, a flexible rubber hose simulating member leading therefrom, a simulated nozzle at the end of the hose member, and a keyhole 40 type slot in one of the side walls of the body for receiving and holding the nozzle member when not in use, said keyhole slot being so dimensioned as to freely receive the nozzle at the enlarged part of the slot, but to hold the nozzle 45 at the narrow part of the slot.

2. A toy gasoline station comprising a base, a battery housing, and a simulated gasoline pump, said pump comprising an upright body member having an electric light socket at the upper end 50 thereof, a lamp bulb having the flat circular shape of the advertising sign ordinarily used on such pumps, the base of said lamp being received in said socket and a conductor leading from the socket downwardly through the pump and beneath the base to the battery casing.

3. A toy gasoline station comprising a metallic base, a building simulating a gasoline station building mounted thereon, a battery housing concealed by said building, and one or more simulated gasoline pumps mounted on said base, each of said pumps comprising an upright body member having a grounded electric light socket at the upper end thereof, a bulb having the flat circular shape of the advertising sign ordinarily used on such pumps, an insulated conductor leading from the socket downwardly through the pump and beneath the base to one terminal of the battery casing, and a switch for grounding 70 the other terminal of said casing.

4. A toy gasoline station comprising a metallic base, a simulated building mounted thereon, a battery housing partially concealed thereby, a plurality of simulated gasoline pumps mounted 75

thereon, and other simulated accessories, each of said pumps comprising an upright body member having a grounded electric light socket at the upper end thereof, a bulb having the flat circular shape of the advertising sign ordinarily used on such pumps, an insulated conductor leading from the socket downwardly through the pump and beneath the base to one terminal of the battery casing, a switch for grounding the other terminal of said casing, a flexible rubber hose simulating member leading from the pump body, a simulated nozzle at the end of the hose member, and a bayonet type slot in the side of the pump body for receiving the nozzle member, said keyhole slot being so dimensioned as to freely receive the nozzle at the enlarged part of the slot, but to hold the nozzle at the narrow part of the slot.

5. A toy automobile lift comprising a base, 20 channeled guide rails, and means for elevating the same, said means including four bent wire arms pivotally mounted at their lower ends on the base and at their upper ends on the guide rails and forming a parallelogram movement, 25 and an integral extension on one arm bent to form a handle for operating said arms to elevate the lift.

6. A toy automobile lift comprising a base, 30 a battery housing, channeled guide rails, and means for elevating the same, an electric light bulb for illuminating the space beneath the lift, a switch near said lift, wiring interconnecting the bulb, the switch and the battery casing, and means for automatically closing the switch whenever the lift is elevated.

7. A toy automobile lift comprising a base, a battery housing, channeled guide rails, and means for elevating the same, said means including bent wire arms mounted at the lower ends on the base and at the upper ends on the guide rails and forming a parallelogram movement, an extension of one arm being formed into a handle for elevating the lift, an electric light bulb for illuminating the space beneath the lift, a switch near said lift, wiring interconnecting the bulb, the switch and the battery casing, and an extension of one arm being formed into means for automatically closing the switch whenever the lift is elevated.

8. A toy automobile lift comprising a sheet metal base having four bearing lugs struck upwardly therefrom in rectangular formation, a sheet metal elevatable support including two laterally disposed guide rails interconnected by two transverse spacer members, said rails and spacer members being flanged to strengthen and rigidify the support and to channel the guide rails, four bearing lugs struck downwardly from said support, two rods each bent to U shape with outwardly turned ends, the center and end portions of said rods being received in the aforesaid bearing lugs of the support and base and forming four arms constituting a parallelogram movement for elevating the support from or 30 lowering the support to the base, and an integral extension on one of said rods bent to form a handle for elevating or lowering the support.

LOUIS MARX. 35
